UNITED STATES PATENT OFFICE.

ABE HARTMAN, OF BROOKLYN, NEW YORK.

DESIGN FOR A TEMPERATURE-INDICATING HOUSING.

Application filed July 15, 1926. Serial No. 18,366. Term of patent 14 years.

To all whom it may concern:

Be it known that I, ABE HARTMAN, a citizen of the United States, residing in Brooklyn, in the county of Kings and State of New York, have invented a new, original, and ornamental Design for a Temperature-Indicating Housing, of which the following is a specification, reference being had to the accompanying drawings, forming part thereof, in which—

Figure 1 is a view in front elevation of my ornamental temperature indicating housing.

Figure 2 is a side view in elevation, and

Figure 3 is a top plan view of the housing as illustrated in Figure 1.

I claim:

The ornamental design for a temperature indicating housing as shown.

ABE HARTMAN. [L. S.]
